(57) **ABSTRACT**

A new *Chrysanthemum* plant named 'Symild Yel' particularly distinguished by the large, yellow inflorescences, medium green foliage, good mounded plant habit and a natural flowering season response of about mid October.

1 Drawing Sheet

1

Latin name of the genus and species of the plant claimed:
Chrysanthemum×morifolium.
Varietal denomination: 'Symild Yel'.

BACKGROUND OF THE NEW PLANT

The present invention comprises a new *Chrysanthemum*, botanically known as *Chrysanthemum×morifolium*, and hereinafter referred to by the variety name 'Symild Yel'.

'Symild Yel' is a product of a planned breeding program. The new cultivar has large, yellow inflorescences, medium green foliage, good mounded plant habit and a natural flowering season response of about mid October.

'Symild Yel' originates as a natural whole plant mutation of 'Yomildred', U.S. Plant Pat. No. 21,187. 'Symild Yel' was discovered and selected by the inventor as a single flowering plant within a population of the parent cultivar in a controlled breeding program in Alva, Fla. in December 2008. The parent cultivar 'Yomildred' has white inflorescence color, a little larger plant habit and a natural season flowering response that is a few days faster.

The first act of asexual reproduction of 'Symild Yel' was accomplished when vegetative cuttings were propagated from the initial selection in January 2008 in a controlled environment in Alva, Fla.

BRIEF SUMMARY OF INVENTION

Horticultural examination of plants grown from cuttings of the plant initiated in January 2008, and continuing thereafter, has demonstrated that the combination of characteristics as herein disclosed for 'Symild Yel' are firmly fixed and are retained through successive generations of asexual reproduction.

'Symild Yel' has not been observed under all possible environmental conditions. The phenotype may vary significantly with variations in environment such as temperature, light intensity and day length.

A Plant Breeder's Right for this cultivar was applied for in Canada on Apr. 9, 2010 (No. 10-6933). 'Symild Yel' has not been made publicly available more than one year prior to the filing of this application.

2

The following traits have been repeatedly observed and are determined to be basic characteristics of the new variety. The combination of these characteristics distinguishes this *Chrysanthemum* as a new and distinct variety.

5 BRIEF DESCRIPTION OF THE PHOTOGRAPHS

The accompanying photographic drawing shows typical flower and foliage characteristics of 'Symild Yel' with colors being as true as possible with an illustration of this type. The photographic drawing shows a flowering potted plant of the new variety.

DETAILED BOTANICAL DESCRIPTION

15 The plant used for the photographs was about 16 weeks old grown in Monroeville, N.J. in an outdoor trial. One rooted cuttings grown in a nine inch pot with no terminal pinching of the apices. The photograph was taken in mid October 2010 in New Jersey.

20 The plant descriptions and measurements were taken in Gilroy, Calif. in May 2010 under natural light. Plants were grown under conditions which approximate those generally used for potted *Chrysanthemum* trials in a greenhouse. These plants used in the descriptions were about 10 weeks old.

25 Color references are made to The Royal Horticultural Society Colour Chart (R.H.S.) 2001.

TABLE 1

30 DIFFERENCES BETWEEN THE NEW VARIETY 'SYMILD YEL' AND A SIMILAR VARIETY		
	'Symild Yel'	'Sunny Yobrigitte' (U.S. Plant Pat. No. 13,973)
Inflorescence size:	Little larger	Little smaller
Plant habit:	More mounded/less height/more width	Less mounded/more upright

Plant:

Form, growth, and habit.—Herbaceous decorative garden-type, stems upright and outwardly spreading, freely branching, strong and moderately Vigorous growth habit.

<i>Plant height.</i> —10-12 cm.		<i>Mature inflorescence:</i>
<i>Plant height (inflorescence included).</i> —18-20 cm.		<i>Diameter.</i> —7-7.5 cm.
<i>Plant width.</i> —20-23 cm.		<i>Depth.</i> —2.0-2.5 cm.
<i>Garden performance and tolerance to weather.</i> —Very good.	5	<i>Total diameter of 'disc'.</i> —0.3-0.4 cm (but not visible).
<i>Roots:</i>		<i>Receptacle height.</i> —0.3-0.5 cm.
<i>Number of days to initiate roots.</i> —4 days at about 22 degrees C.		<i>Receptacle diameter.</i> —0.6-0.7 cm.
<i>Number of days to produce a rooted cutting.</i> —10-12 days at 22 degrees C.	10	<i>Ray florets:</i>
<i>Type.</i> —Fine, fibrous, free branching.		<i>Average quantity of florets.</i> —150 in numerous whorls.
<i>Color.</i> —RHS N155B but whiter.		<i>Color of florets, upper surface.</i> —RHS 4B with RHS 4A apex; sometimes fading to RHS 4C.
<i>Foliage:</i>		<i>Lower surface.</i> —RHS 4D.
<i>Arrangement.</i> —Alternate.		<i>Length.</i> —2.9-3.2 cm.
<i>Immature, leaf color, upper surface.</i> —RHS 137A but a little darker.	15	<i>Width.</i> —0.7-0.8 cm.
<i>Lower surface.</i> —Closest to RHS 138B.		<i>Shape.</i> —Elliptical.
<i>Mature, leaf color, upper surface.</i> —RHS 137A but a little darker.		<i>Apex shape.</i> —Praemorse.
<i>Lower surface.</i> —Closest to RHS 138B.	20	<i>Margin.</i> —Entire.
<i>Length.</i> —6.0-6.5 cm.		<i>Texture, upper surface.</i> —Papillose.
<i>Width.</i> —3.8-4.5 cm.		<i>Lower surface.</i> —Papillose.
<i>Shape.</i> —Ovate.		<i>Disc florets:</i>
<i>Base shape.</i> —Attenuate.		<i>Average quantity of florets.</i> —7-10.
<i>Apex shape.</i> —Acute to apiculate.		<i>Color of florets.</i> —RHS 1C but more green with RHS 1A apex.
<i>Margin.</i> —Irregularly and palmately lobed; serrate.		<i>Length.</i> —0.5-0.6 cm.
<i>Texture, upper surface.</i> —Bifid T-shaped hairs.		<i>Width.</i> —0.1 cm.
<i>Lower surface.</i> —Bifid T-shaped hairs.		<i>Shape.</i> —Tubular, elongated.
<i>Color of veins, upper surface.</i> —Closest to RHS 144A.		<i>Apex shape.</i> —Acute, 5 pointed.
<i>Color of veins, lower surface.</i> —Closest to RHS 144A.	30	<i>Phyllaries:</i>
<i>Petiole color.</i> —Closest to RHS 144A.		<i>Quantity.</i> —28-30.
<i>Length.</i> —2.2-2.9 cm.		<i>Color, upper surface.</i> —RHS 137A to RHS 137B.
<i>Diameter.</i> —0.2 cm.		<i>Lower surface.</i> —RHS 137A to RHS 137B.
<i>Texture.</i> —Heavily Bifid T-shaped hairs.	35	<i>Length.</i> —0.8-0.9 cm.
<i>Stem:</i>		<i>Width.</i> —0.15 cm.
<i>Quantity of main branches per plant.</i> —5-6.		<i>Shape.</i> —Lanceolate.
<i>Color of stem.</i> —RHS 146A.		<i>Apex shape.</i> —Acute.
<i>Length of stem.</i> —12-15 cm.		<i>Base.</i> —Fused.
<i>Diameter.</i> —0.3-0.5 cm.		<i>Margins.</i> —Entire.
<i>Length of internodes.</i> —0.4-0.7 cm.		<i>Texture, upper surface.</i> —Bifid T-shaped hairs.
<i>Texture.</i> —Bifid T-shaped hairs.		<i>Lower surface.</i> —Bifid T-shaped hairs.
<i>Color of peduncle.</i> —RHS 146A.		<i>Reproductive organs:</i>
<i>Length of peduncle.</i> —7-10 cm.	40	<i>Pistil.</i> —1.
<i>Peduncle diameter.</i> —0.2-0.25 cm.		<i>Length.</i> —0.5 cm.
<i>Texture.</i> —Bifid T-shaped hairs.	45	<i>Style color.</i> —RHS 1C.
<i>Inflorescence:</i>		<i>Style length.</i> —0.3-0.4 cm.
<i>Type.</i> —Compositae type, solitary inflorescences, decorative-type, borne terminally above foliage, ray florets arranged acropetally on a capitulum.		<i>Stigma color.</i> —RHS 12A.
<i>Quantity of short days to flowering (response time).</i> —	50	<i>Stigma shape.</i> —Bi-parted.
Approximately 55 days.		<i>Ovary color.</i> —Not observed.
<i>Quantity of inflorescences per plant.</i> —50-55.		<i>Stamens.</i> —1.
<i>Lastingness of individual blooms on the plant.</i> —About 6 weeks from the first color.		<i>Color of filaments.</i> —RHS 1C.
<i>Fragrance.</i> —Slightly spicy.		<i>Length filaments.</i> —0.2-0.3 cm.
<i>Bud (just when opening/showing color):</i>		<i>Anther color.</i> —RHS 17B.
<i>Color.</i> —RHS 4B with RHS 4A apex.		<i>Anther length.</i> —0.15 cm.
<i>Length.</i> —0.5-0.9 cm.		<i>Anther shape.</i> —Oval.
<i>Width.</i> —0.5-0.6 cm.		<i>Color of pollen.</i> —RHS 17A.
<i>Shape.</i> —Oblate.		<i>Pollen amount.</i> —Some observed.
<i>Immature inflorescence:</i>		<i>Fertility/seed set.</i> —Has not been observed on this hybrid.
<i>Diameter.</i> —5.0-5.5 cm.		<i>Disease/pest resistance:</i> Disease/pest resistance has not been observed on this hybrid.
<i>Color of ray florets, upper surface.</i> —RHS 4A.		<i>What is claimed is:</i>
<i>Lower surface.</i> —RHS 4D.	60	1. A new and distinct variety of <i>Chrysanthemum</i> plant named 'Symild Yel' substantially as illustrated and described herein.
